UNITED STATES PATENT OFFICE

149,633

DESIGN FOR A COMBINED ASH TRAY, CIGARETTE LIGHTER, AND BOOK END

Lanny Grey, New York, N. Y.

Application November 30, 1946, Serial No. 135,191

Term of patent 7 years

(Cl. D85—2)

To all whom it may concern:

Be it known that I, Lanny Grey, a citizen of the United States, residing at New York, in the county of New York and State of New York, have invented a new, original, and ornamental Design for a Combined Ash Tray, Cigarette Lighter, and Book End, of which the following is a full specification, reference being had to the accompanying drawing, forming a part thereof.

In the drawing:

Fig. 1 is a side elevational view of a combined ash tray, cigarette lighter and book end showing my new design;

Fig. 2 is a perspective view thereof as it appears with the lighter in raised position;

Fig. 3 is a top plan view; and

Fig. 4 is a rear elevational view of the same.
I claim:

The ornamental design for a combined ash tray, cigarette lighter, and book end, as shown.

LANNY GREY.
